Frank Warren
ATTORNEY

UNITED STATES PATENT OFFICE.

FREDERICK W. CHRISWELL, OF SEATTLE, WASHINGTON.

BOLSTER PLATE.

Application filed August 6, 1925. Serial No. 48,453.

This invention relates to improvements in bolster plates for use on logging cars and the object of this invention is to provide a one piece bolster plate that is strong and durable in construction and that will not be broken by ordinary use.

Another object is to provide a cast metal bolster plate shaped to fulfill certain requirements but designed so as to avoid producing internal stresses and crystal deformation in the metal as the casting cools.

These bolster plates are commonly used on logging cars for supporting car bunks thereon, the bolster plates resting on the usual cross bolster of the car.

Bolster plates of this nature as heretofore constructed have not been satisfactory, due to the fact that they are liable to break near the location of the central hub under ordinary condition of use. This weakness is not due to lack of the necessary weight or amount of material at the location where the breaks occur but rather to the fact that the casting is shaped so that the crystals in the material at that particular location are deformed, compressed and left under permanent stress as the casting cools, thus leaving them in a state in which they break easily.

The present invention overcomes this difficulty by providing a bolster plate that eliminates this deformation in the material.

I accomplish the objects by devices illustrated in the accompanying drawings wherein,—

Figure 1 is a view in side elevation of a bolster plate constructed in accordance with this invention.

Fig. 2 is a view in longitudinal midsection of the same.

Figs. 3 and 4 are bottom and top plan views respectively of the same.

Figs. 5, 6, and 7 are views in cross section on broken lines 5—5, 6—6, and 7—7 respectively of Fig. 3.

Referring to the drawings, throughout which like reference numerals designate like parts, Figs. 1 to 7 inclusive indicate a preferred form of bolster plate of one piece integral construction and of substantially rectangular form that is adapted to be used upon the bolster of a logging car to support a relatively heavy log bunk on which logs are carried. The weight of the log bunk rests wholly upon the ends of the bolster plate as shown in Fig. 1 thereby producing

a strain where the web members meet the outer hub member as indicated by the arrows in Fig. 1. The bolster plate has a flat top side 12, as shown in Fig. 4, and a bottom side shown in Fig. 5, that is provided with cored portions 13 leaving at each side longitudinal webs 14 and midway between the two sides other longitudinal webs 15 that are thickened, as at 16, near the center of the bolster plate.

A larger hub 17 extends downwardly from the center of the bolster plate and a smaller hub 18 extends upwardly from the bottom 19 of the larger hub 17. The upper end of the smaller hub 18 has a hole 20 of smaller diameter than the interior of said smaller hub 18. The webs 14 and 16 all terminate in and are integral with the larger hub 17. The top side of the bolster plate is cored, as at 21 and 22, to leave relatively long recesses in the longitudinal medial plane of the plate and the inner ends of said cored recesses 21 and 22 are cored deeper, as at 23 and 24, said deeper portions extending down between the walls of the larger hub portion 17 and the small hub portion 18.

It will be noted that the thickened webs 16 on the bottom with the recesses 21, 22, 23, and 24 on the top leaves in effect two ribs of metal that extend continuously across the bolster plate on opposite sides of the hub 18.

Arcuate recesses 25 and 26 are formed in the top side of the bolster plate to the front and rear of the center and extend down between hubs 17 and 18, said recesses 25 and 26 are both undercut at both ends as indicated at 27 to reduce the weight of the bolster plate as much as possible and yet leave relatively wide and substantial webs 28 of metal connecting the central hub 18 with the remainder of the bolster plate body at four points between the cored recesses 25, 24, 26, and 23, two of the webs 28 being on each side of the smaller hub 18.

It will be noted that the webs 28 on the top side and the widened portions 16 of webs 15 on the bottom side are all integrally connected with hub 17 thus greatly strengthening the structure and tending to prevent the bolster plate from breaking within or around the hub portion. Flanges 30 are provided both on the front and rear sides of the bolster plate to afford a wider bearing surface.

Square corners and deep recesses are avoided as much as possible in the construction around the hub so that when the bolster plate is cooling in the process of casting it will not be subjected to excessive strains sufficient to deform the crystals of the metal due to compression of the molding sand in pockets.

The invention shown provides the relatively wide webs 28, two on each side of the smaller hub both extending continuously across the bolster plate so as to prevent normal contraction of metal as the bolster plate cools in casting. These webs are also located so as to afford the greatest resistance to transverse breakage. Abnormal stresses are also reduced by providing relatively shallow pockets with rounded corners so that the wedging of the molding sand and consequent deformation of the crystals of the metal in cooling will be reduced to a minimum. This is especially apparent in the provision of recesses 21—23 and 22—24, the recesses 21 and 22 extending well outwardly and tapering to points as shown and the corners being rounded instead of square where recesses 21 and 22 intersect recesses 23 and 24 respectively.

The foregoing description and accompanying drawings clearly disclose a preferred embodiment of this invention but it will be understood that this disclosure is merely illustrative and that such changes in the device may be made as are within the scope and spirit of the following claims.

What I claim is:—

1. A bolster plate of the class described, embodying a body portion, two integral concentric hubs in said bolster plate arranged in relatively spaced relation one within the other and a plurality of integral web members on each side of the longitudinal center line of said bolster plate extending across the space between said two hub members.
2. A bolster plate of the class described, embodying a relatively long rectangular body member, a large integral hub extending downwardly from the center of said

body member, a small integral hub extending upwardly within and spaced from said larger hub, and two longitudinal webs extending across the space between said hubs on each side of the longitudinal center line of said bolster plate and uniting with portions of said smaller hub to form a continuous metal bridge across the central portion of said bolster plate.

3. A bolster plate of the class described, embodying a relatively long body member, two integral concentric hubs of different size disposed centrally of said bolster plate and arranged concentrically one within the other in spaced relation, web members on the bottom side of said bolster plate mid way between the two sides and having relatively wide portions that merge with said outer hub, said bolster plate having longitudinal recesses on its front side opposite said wider rib portions and having longitudinal ribs on opposite sides of said recesses extending across the space between said two hubs and merging with said inner hub.

4. A bolster plate of the class described embodying a relatively long body member, a larger integral hub extending downwardly from the center of said body member, a smaller integral hub extending upwardly concentrically within said larger hub and leaving an annular space between the walls of said two hubs, webs on the bottom of said bolster plates at the sides thereof and merging with said larger hub, other webs on the bottom of said bolster plate mid way between the two sides thereof and having relatively wide portions that merge with said outer hub, said bolster plate having longitudinal recesses on its top side that extend down into said wider web portions and are deeper at the location of said annular space between said two hubs and longitudinal ribs on opposite sides of said recesses extending across the space between said two hubs and being substantially tangent to said inner hub.

In witness whereof, I hereunto subscribe my name this 20th day of July, A. D. 1925.

FREDERICK W. CHRISWELL.
